LOCOMOTIVE BOILER SUPERHEATER

Lloyd B. Jones, Altoona, and Ralph T. Stratton, Philadelphia, Pa., assignors to The Pennsylvania Railroad Company, Philadelphia, Pa., a corporation of Pennsylvania

Application August 12, 1938, Serial No. 224,495

7 Claims. (Cl. 122—462)

This invention relates to steam boiler superheaters, and especially to superheaters comprising loop tubes which extend from a smoke box or end chamber of a boiler into boiler flues or fire tubes that open into the chamber. Such superheaters are much used with steam locomotive boilers of horizontal fire tube type, and the invention is explained hereinafter with particular reference to this field of use. The invention aims at improving the arrangement and construction of such superheaters, at securing high superheat, at minimizing the pressure drop of steam in the superheater, and at facilitating inspection, repair, and replacements of superheater tubes. Other features and advantages of the invention will appear from the following description of a species or form of embodiment, and from the drawings. All the features and combinations shown or described are, indeed, of our invention, so far as novel over the prior art.

Fig. I shows a vertical section through the front end of a locomotive boiler equipped with a superheater embodying our invention, one of the main headers and one of the subheaders being also shown in vertical section, and part of another subheader being broken away.

Fig. II is a front view of a locomotive boiler equipped with such a superheater, the boiler shell being in section, with portions broken away, and various parts of the superheater being in section, broken away, and removed.

Fig. III is a fragmentary front view similar to Fig. II, but with the forward header and subheaders of the superheater removed.

Fig. IV shows a vertical section through a portion of one of the main superheater headers, taken as indicated by the line and arrows IV—IV in Fig. I.

Fig. V shows a vertical mid-section through one of the main superheater headers, taken as indicated by the line and arrows V—V in Fig. III.

Fig. VI shows two of the subheaders of the superheater in horizontal section, taken as indicated by the line and arrows VI—VI in Fig. I, portions of the superheater tubes connected to these subheaders being also shown.

Fig. VII is a partial view of the main steam delivery header and of the subheaders of the superheater from in front, looking rearward and upward, as indicated by the line and arrows VII—VII in Fig. I, most of the main steam supply header being omitted to avoid confusion.

In Figs. I, II, and III of the drawings, 10 is the front tube sheet or flue sheet of a locomotive

boiler of fire tube type; 11 is the main boiler shell; 12 is a forward extension of the main boiler shell, enclosing the front end chamber or smoke box 13; 14 are the fire tubes extending through the water space of the boiler, and opening through 10 into the smoke box 13; and 15 are the large fire tubes or flues, that accommodate the steam tubes 16 of the superheater, which are shown as single U-loops. As shown in Fig. II, the flues 15 are arranged in vertical 10 rows, and so likewise are the loop-tubes 18, of which there are two in each flue. The superheater is shown as comprising transverse main steam supply and delivery headers 20 and 21 adjacent one another in the top of the smoke 15 box, with sets of steam supply and delivery sub-headers 22 and 23 extending downward from them in front of the flue sheet 10. As shown in Fig. I, the upper ends of the subheaders 22 and 23 overlap in front of the corresponding main 20 headers 20 and 21 which these subheaders mainly underlie, and are attached to them from in front, preferably on a slope as hereinafter described.

As best shown in Figs. I—V, the main steam 25 supply header 20 has an inlet opening 24 in its rear side, with a surrounding flange 25, and is attached to the front flue sheet 10 and connected to the boiler dry-pipe 26 by bolts 27, most of which take through said flange. However, as 30 shown in Figs. III, IV, and V, a portion of the flange 25 is merged with the rear wall of the header 20, and the nuts 28 for the bolts 27 in this portion are accommodated in tubular "barrels" 29 forming part of the header casting, and opening from the front of the header back to its rear end around the bolts, so that the nuts 28 may be applied and removed with a socket wrench introduced through these barrels. As shown in Figs. 35 III—V, the main supply header 20 tapers to either 40 side from the inlet opening 24. Along its lower front edge, this header 20 has a series of openings and seats for the subheaders 22, consisting of short necks 30 with flanges or ears 31 at their ends for the attachment of the subheaders 45 22, by means of fastenings such as bolts 32 taking through the flanges or ears 31 and through similar flanges or ears 33 on the upper neck portions 34 of said subheaders 22. As most clearly shown in Fig. I, these openings and seats lie on a slope 50 rearward and downward toward the flue sheet 10, so that they are presented obliquely forward and downward away from the flue sheet.

The main transverse steam delivery header 21 is mounted in the top of the smoke box 13 in 55

front of (and somewhat above) the steam supply header 20, substantially over the steam supply subheaders 22, and has outlet openings and seats for the attachment of the subheaders 23, consisting of downward extending necks 35 with flanges or ears 36 (similar to the flanges 31 of the necks 30) for the attachment of the subheaders 23, by means of fastenings such as bolts 37 taking through the flanges or ears 36 and through similar flanges or ears 38 on the upper neck portions 39 of the subheaders 23. As in the case of the supply header 20, the openings and seats of the delivery header 21 lie on a slope rearward and downward toward the flue sheet 10, and are thus presented obliquely forward and downward, away from said flue sheet. As shown in Figs. I and II, the main steam delivery header 21 is located at a substantial interval in front of the main steam supply header 20, so as to minimize direct radiation of heat from the one header to the other, but is attached to the header 20 (and supported therefrom) by bolts 40 taking through bracket lugs 41, 41 on the two headers. The ends of both main headers 20 and 21 are also provided with supporting bracket feet 42 resting on and bolted to brackets 43, which are riveted to the interior of the smoke box shell 12.

As shown in Figs. I, II, and III, the subheaders 22, 23 of both sets abut and are attached to the corresponding main headers 20, 21 at different levels, preferably on a slope (as of about 45 degree) and in a common plane.

As shown in Figs. I, II, and VI, the subheaders 22 and 23 are spaced from one another by a substantial interval, to minimize direct radiation between them, but are attached to one another and kept in proper relative positions by bolted connections between bracket lugs 44, 44 on their adjacent sides. While the necks 30 and 35 of corresponding subheaders 22, 23 of the two sets are directly aligned one in front of another as shown in Fig. II, the lower portions of such corresponding subheaders are oppositely offset, out of line with one another, so that the ends of each loop tube 16 may extend and be connected directly into the rear sides of these subheaders, as shown in Fig. VI.

Preferably, the loop tubes 16 are simply elongated U-tubes in which the steam makes a single pass rearward from the subheader 22 and forward again into the subheader 23, each pair of subheaders 22, 23 serving one vertical row of the tubes. In effect, each such pair of headers 22, 23 with their interconnecting tubes 16 constitute an independent superheater unit, traversed by the steam in parallel with the other such units, and removable or insertable in place by itself, as explained hereinafter.

Important features of the construction shown are the location of both main headers 20, 21 at the top of the smoke box, and the detachability of the subheaders 22, 23 there; for in practice the smoke box contains some parts which it would be undesirable to remove to obtain access to joints and securing devices in the lower portion of the smoke box, as would be necessary if one of the main headers were located there. Furthermore, it is much easier for a workman to work upward or overhead on securing devices for the subheaders than to work downward on them. Important also is the lateral offset of the lower portions of corresponding subheaders 22, 23, to permit direct connection of the tubes 16 of each vertical row directly to their rear sides, while their upper portions or necks 34, 39 are alined,

so that access may be had between the front necks 39 to the fastenings 32 associated with the rear necks 34, etc.

Another important feature is the attachment of the subheaders 22, 23 to the main headers 20, 21 at different levels, and preferably on a slope. If the heads of the fastening bolts 32 for the rear headers 22 were at substantially the same level as those for the bolts 37, it would be impossible to work on them with a wrench between the header necks 34, 39 and behind the bolts 37; and even with these nuts at different levels, it would be very difficult to work on them between the header necks if the axes of the bolts were vertical. With the arrangement shown, however, a socket wrench can be introduced (on a slope upward and rearward) between the front headers 23, and can be applied and operated on the nuts of the bolts 32 for the rear headers, since the nuts for any of the bolts 32, 37 are exposed and visible between the headers 22, 23 at either side of the plane of the bolts. The sloping attachment of the subheaders 22, 23 to the main headers 20, 21 also makes it very easy to withdraw forward any superheater unit (composed of a vertical row of tubes 16 and the headers 22, 23 to which they are connected), by a simple forward movement, without disturbing any other subheaders.

Having thus described our invention, we claim:

1. In a superheater for a horizontal flue boiler, comprising loop tubes extending from a smoke box or end chamber, into which the boiler flues open, back into said flues, the combination of a main transverse steam supply header in the top of the smoke box secured to the end of the boiler above said flues, with a set of detachable downward extending steam supply subheaders for serving said loop tubes overlapping and attached to said main steam supply header in front thereof; a main transverse steam delivery header in the top of the smoke box, detachably mounted on said main steam supply header; and a separate set of detachable steam delivery subheaders, for serving said loop tubes, overlapping and attached to said main steam delivery header in front thereof, and extending downward in front of said steam supply subheaders, and detachably secured to the latter, said loop tubes interconnecting corresponding subheaders of the two sets; whereby, on detaching said main steam delivery header and said steam supply subheaders from said main steam supply header, the entire superheater, excepting said main steam supply header, can be withdrawn forward from the smoke box as a unit, while on detaching corresponding subheaders of the two sets from both the main headers, said detached subheaders and the loop tubes interconnecting them can be withdrawn forward from the smoke box without disturbing other parts.

2. In a superheater for a horizontal flue boiler, comprising loop tubes extending rearward from a smoke box or end chamber, into which the boiler flues open through a flue sheet of the boiler, back into said flues, the combination of separate adjacent transverse main steam supply and delivery headers in the top of the smoke box in front of said flue sheet, said main headers having subheader openings lying on a slope downward and rearward toward said flue sheet and thus presented downward and forward in the smoke box, away from the flue sheet; separate sets of steam supply and delivery subheaders for said loop tubes arranged in front of and underlying

the corresponding main headers, with intervals between their upper portions, and having openings in their said upper portions presented rearward and upward to the said main header openings; and fastenings accessible from below and in front of said subheaders through said intervals between their said upper portions and detachably securing the subheaders to the corresponding main headers in communication with them through the aforesaid main header and subheader openings; the subheaders of said sets being separable from the main headers, when detached, by mere forward displacement, by virtue of their relations to the main headers as hereinbefore set forth.

3. In a superheater for a horizontal flue boiler, comprising loop tubes extending rearward from a smoke box or end chamber, into which the boiler flues open through a flue sheet of the boiler, back into said flues, the combination of separate adjacent transverse main steam supply and delivery headers arranged in the top of the smoke box in front of said flue sheet and one in front of the other, and having subheader seats lying on a slope downward and rearward toward said flue sheet, and thus presented downward and forward in the smoke box, away from said flue sheet, the subheader seats of the forward main header lying in front of and above those of the other main header; and separate sets of steam supply and delivery subheaders for said loop tubes arranged in front of and underlying the corresponding main headers, with intervals between their upper portions, and having their said upper portions detachably secured against corresponding main header seats, so that the joints between said subheaders and the main headers are accessible from below and in front through said intervals between the said upper portions of the subheaders.

4. In a superheater for a horizontal flue boiler, comprising loop tubes extending from a smoke box or end chamber, into which the boiler flues open through a flue sheet of the boiler, back into said flues, the combination of separate adjacent transverse main steam supply and delivery headers in the top of the smoke box in front of said flue sheet; separate sets of steam supply and delivery subheaders, one set in front of the other, having their upper portions substantially aligned, fore and aft of the smoke box, with lateral intervals between them, while their lower portions are offset relative to said upper portions, transversely of the smoke box, out of fore and aft alignment, so that the loop tubes in the boiler flues may extend forward to the rear sides of these lower portions of the subheaders of said sets and be connected into them; and means for detachably connecting said sets of subheaders to the corresponding main headers, the connecting means for the subheaders of at least one of said sets comprising fastenings exposed forward in said intervals, and thus accessible from in front between said upper portions of the subheaders.

5. In a superheater for a horizontal flue boiler, comprising loop tubes extending from a smoke box or end chamber, into which the boiler flues open through a flue sheet of the boiler, back into said flues, the combination of separate adjacent transverse main steam supply and delivery headers in the top of the smoke box in front of said flue sheet; and separate sets of steam supply

and delivery subheaders, one set in front of the other, underlying and detachably attached to the corresponding main headers on a slope downward and rearward toward said flue sheet; the upper portions of corresponding subheaders of said sets being substantially aligned, fore and aft of the smoke box, with intervals between those of each set through which the joints between said subheaders and the main headers may be reached from below and in front, while the lower portions of said corresponding subheaders are offset relative to said upper portions, transversely of the smoke box, out of fore and aft alignment, so that the loop tubes in the boiler flues may extend forward to the rear sides of these lower portions of the subheaders of both sets and be connected into them.

6. In a superheater for a horizontal flue boiler, comprising loop tubes extending rearward from a smoke box or end chamber, into which the boiler flues open through a flue sheet of the boiler, back into said flues, the combination of separate adjacent transverse main steam supply and delivery headers in the top of the smoke box, in front of said flue sheet, said main headers having externally flanged subheader necks, with intervals between them, presenting their openings or mouths downward and forward in the smoke box, away from said flue sheet but on a slope downward and rearward toward it, the mouths of the necks of one main header lying in front of and above those of the other main header, substantially in fore and aft alignment with them; separate sets of steam supply and delivery subheaders having externally flanged upper portions, with lateral intervals between them, arranged in front of and underlying the corresponding main header necks, substantially in fore and aft alignment, while their lower portions are offset relative to said upper portions, transversely of the smoke box, out of fore and aft alignment, so that the loop tubes in the boiler flues may extend forward to the rear sides of these lower portions of said subheaders and be connected into them; and bolts taking through the flanges of corresponding main header necks and subheaders and detachably securing the subheaders to the main headers; said bolts being thus accessible from below and in front of said subheaders through said intervals between the subheader necks, and the subheaders of both sets being separable from the main headers, when detached, by mere forward displacement, by virtue of their relations to the main headers as hereinbefore set forth.

7. In a superheater for a horizontal flue boiler, comprising loop tubes extending rearward from a smoke box or end chamber, into which the boiler flues open through a flue sheet of the boiler, back into said flues, the combination of separate adjacent transverse main steam supply and delivery headers in the top of the smoke box, in front of said flue sheet, said main headers having externally flanged subheader necks, with lateral intervals between them, presenting their openings or mouths downward and forward in the smoke box, away from said flue sheet but on a slope downward and rearward toward it, the mouths of one main header lying in front of and above those of the other main header, substantially in fore and aft alignment with them.

LLOYD B. JONES.
RALPH T. STRATTAN.
